[57] ABSTRACT

A stamped base plate (16) for a signage assembly (10) that includes elongated slots (20, 40) and canted flanges (18, 38) that engage a back channel of an elongated sign plate (12). The base plate has protrusions (34) that engage hook (30) of an end cap (14). The base plate can be cut to length at score lines (44) aligned with the slots (20, 40).

STAMPED BASED PLATE FOR INTERIOR SIGNAGE

TECHNICAL FIELD

The field of this invention relates interior signage and more particularly to a base plate, for modular interior signage.

BACKGROUND OF THE DISCLOSURE

Interior signage is very useful for hospitals, educational campuses, museums, and office buildings for room identification, personnel identification, directions, and directories. Modular signage has become popular because of its particularly advantage when there are frequent changes in personnel, relocation of internal departments, or other information. When one portion of the signage needs revision, a particular element or section can be replaced with the other labels remaining untouched or merely relocated.

Modular signage includes individual elongated labels or plates that are individually mounted onto a base plate. End caps are then spring mounted to aesthetically trim out the signage and to deter casual and unauthorized removal of the end cans and labels.

The elongated plates are mounted on a singular base plate that has beveled channels running almost the entire width of the plate. The plate made from aluminum needs to have the channels machined therein which is a costly operation. The base plate needs to be sized at the factory and is not amenable to change in size at the end site of the signage. As such, blank elongated plates are often used as filler when fewer labels are needed. These blank spots are often undesirable from both an aesthetic and marketing viewpoint.

What is needed is a base plate for a modular signage assembly that can be easily mounted on a wall and can be easily manufactured and easily cut to length on site as needed.

SUMMARY OF THE DISCLOSURE

In accordance with one aspect of the invention, a modular interior signage assembly includes a plurality of elongated sign plates each with a rear facing open-ended channel with undercut side flanges. A pair of base plates for attaching to a substrate such as a wall or other platform are spaced apart to be in proximity to respective opposing ends of the elongated sign plates. Each base plate has a first set of a plurality of elongated cutouts that extend between opposing edges of the base plate. A first set of a plurality of flanges on the base plate extend from opposing edges of the elongated cut outs for engagement to the undercut side flanges of the rear facing channel of the elongated sign plates. The flanges retain the elongated plates laterally on said base plate. Preferably the flanges are canted outwardly from the base plate. The undercut side flanges have a bevel cant to complement the canted angle of the flanges.

End caps engage a respective outer edge of each base plate. Preferably, a spring clip is interposed between two adjacent flanges of the first set. Preferably, the end cap has a hook that is inserted in a gap between the elongated plate and the base plate and engages a protrusion interposed between the edge of the base plate and the first set of flanges. The spring clip biases the hook section to retain engagement with said protrusion. The spring clip has a rear extending leg portion that is engageable in an aperture through the base plate positioned between the two adjacent flanges.

It is desirable that the base plate has a second set of cutouts spaced toward an inner lateral edge of the base plate.

The second set of cutouts has a second set of flanges at opposing edges of the elongated cut outs of the second set. The flanges engage the undercut side flanges of the rear-facing channel of elongated sign plates to retain the plates laterally on the base plate. The second set of flanges are staggered with respect to the first set of flanges to retain every other elongated sign plates at different positions from the plates retained by the first set of flanges. In one embodiment, the first set of elongated slots and second set of slots are horizontally aligned and spaced apart to form a cuttable web therebetween. The web is scored to promote ease of cutting or fragmenting at the score. The base plate can be cut to length at the web and at each edge aligned with a cutout from the first set and a cut out from said second set.

In accordance with another aspect of the invention, a base plate for a modular signage assembly includes a first set of a plurality of elongated cutouts that extend between opposing edges of the base plate. A first set of flanges on the base plate extend from opposing edges of the elongated cut outs for engagement to undercut side flanges of a rear facing channel in an elongated sign plate to retain the elongated plates laterally on the base plate. Preferably, the base plate has a second set of cutouts spaced toward an inner lateral edge of said base plate. The second set of cutouts have a second set of flanges extend from the edge of the elongated cut outs of the second set. The flanges are engageable to the undercut side flanges of the rear-facing channel of the elongated sign plates. The flanges retain the plates laterally on the base plate. The second set of flanges are staggered with respect to the first set of flanges to retain said elongated sign plates at different positions than the first set of flanges.

BRIEF DESCRIPTION OF THE DRAWINGS

Reference now is made to the accompanying drawings in which:

FIG. 1 is a perspective view of an assembled modular sign in accordance with one embodiment of the invention;

FIG. 2 is an exploded view of the modular sign shown in FIG. 1;

FIG. 3 is an enlarged front plan view of one base plate shown in FIG. 2;

FIG. 4 is an enlarged back plan view of the base plate shown in FIG. 3;

FIG. 5 is an end view of the plate shown in FIG. 3; and

FIG. 6 is a fragmentary view of a backing plate broken along a score line;

FIG. 7 is an enlarged fragmentary front plan view illustrating the mounting of the end cap, and;

FIG. 8 is a cross-sectional view taken along lines 8—8 shown in FIG. 1.

DETAILED DESCRIPTION OF THE PREFERRED EMBODIMENT

Referring now to FIG. 1, a modular sign 10 is shown in the assembled condition with a plurality of elongated sign plates 12 and two end caps 14. These elongated sign plates 12 and end caps 14 are well known in the art and are commercially available from Infonorm Inc.

As shown in FIG. 2, the sign 10 is illustrated in the exploded and disassembled condition that exposes two backing plates 16. Each backing plate 16 is made from stamped aluminum. The backing plates 16 mount the elongated sign plates 12 and end caps 14 through spring clips 50, and in turn are mounted to a wall or platform or other appropriate substrate 60.

As shown in FIG. 3, a first column of flanges **18** and elongated slots **20** are stamped in the backing plate. The elongated slots and flanges extend generally in the horizontal direction. The flanges **18** are bent from opposing edges **19** of sequential slots **20** to cant generally forwardly as illustrated in FIG. 5. The angle of the flange **18** corresponds to the undercut bevel **22** of rear facing, open-ended channels **24** in the elongated sign plates **12**, as clearly illustrated in FIG. 8. Each flange has a notch **26** therein for receiving a distal end **28** of a hook **30** on end cap **14**. The notch **26** breaks up flange **18** into a long section **32** and a short section **34** of flange **18**. The short section **34** may be referred to a protrusion for engagement with the hook **30** for maintaining the end cap onto the sign **10**. Each elongated slot also has end legs **36** for ease in stamping and bending forward the flanges **18**. The leg **36** outside of protrusion **34** is spaced from outer edge **37** of backing plate **16** to form a side support strip **35**. The protrusion **34** and notch **26** are spaced from the outer edge **37** to retrofit the commercially available end caps **14** such that the hooks **30** are properly positioned and the edge **37** abuts against a rear lip **33** of the end cap **14**.

The spring clip **50** has resilient legs **52** that engage the hook **30** to resiliently bias the hook **30** into the notch **26** and retain engagement of the hook **30** with the protrusion **34**. As shown in FIG. 7 and 8, the spring clip **50** has a rear leg **54** that is pressed fitted or snap fitted into aperture **56** to be seated between two opposing flanges **18** as shown in FIG. 6. The spring clip **50** is also retained in its proper orientation by the flanges **18**. The end cap can be manually assembled and disassembled onto and off of the sign **10** by overcoming the resilient bias of the leg **52**. Preferably, springs **50** are mounted near the top and bottom of end cap **14**.

A second column of flanges **38** and elongated slots **40** are in staggered relationship with the first sets **18** and **20**. The construction of the flanges **38** and slots **40** are identical to flanges **18** and slots **20** apart from being mirror imaged and vertically staggered with respect to the first column. The flanges **38** extend from opposing edges **39** of sequential slots **40**. Like components of these flanges **38** and slots **40** have the same numerals as labeled for the first sets **18** and **20**. The flanges are staggered such that adjacent single width elongated sign plates **12** are mounted alternately to flanges **18** of the first column and flanges **38** of the second column.

The elongated slots **40** are aligned with the elongated slots **20** such that an intermediate web **42** is formed between the slots **20** and **40**. Each web **42** is vertically aligned with respective side support strips **35**. Each web **42** and strip **35** is scored to promote fragmentation and cutting along the score lines **44** as illustrated in FIG. 6.

Referring now to FIGS. 2 and 8, each backing plate **16** is mounted onto a wall or other platform **60** by adhesive or fasteners **58** passing through mounting holes **46**. The backing plates **16** are each cut along the desired score line **44** as shown in FIG. 6 to the desired length to accommodate the desired number of elongated plates **12**. The backing plates **16** when mounted are appropriately spaced to accommodate the desired length of the elongated plates **12**.

In this fashion, stamped backing plates **16** can replace expensive machined backing plates. The backing plates can be cut and arranged to accommodate a wide variety of sign sizes. The cutting can be done on site during installation of the sign. The staggered nature of the first set of flanges **18** and slots **20** and second sets of flanges **38** and slots **40** provided for a symmetrical backing plate **12** with no need for concern of left or right handedness while providing for a structurally supportive center web **42**.

Variations and modifications are possible without departing from the scope and spirit of the present invention as defined by the appended claims.

The embodiments in which an exclusive property or privilege is claimed are defined as follows:

1. A modular interior signage assembly characterized by: a plurality of elongated sign plates each with a rear facing open-ended channel with undercut side flanges; a pair of base plates for attachment to a substrate and spaced apart to be in proximity to respective opposing ends of the elongated sign plates; said pair of base plates having a first set of a plurality of elongated slots that extend between opposing edges of the base plate, a first set of flanges on said base plate at respective opposing edges of said elongated slots for engagement to said undercut side flanges of the rear facing channel of said elongated sign plates to retain said elongated sign plates laterally on said base plate; a pair of end caps engageable to a respective outer edge of each base plate.

2. A modular interior signage assembly as defined in claim 1 further characterized by:

each of said base plates having a second set of slots spaced toward an inner lateral edge of a respective base plate, said second set of slots having a second set of flanges at respective opposing edges of said elongated slots of said second set for engagement to said undercut side flanges of the rear facing channel of said elongated sign plates to retain said elongated plates laterally on said pair of base plates, said second set of flanges being staggered with respect to said first set of flanges to retain said elongated sign plates at different vertical positions than the elongated sign plates mounted on said first set of flanges.

3. A modular interior signage assembly as defined in claim 2 further characterized by:

said slots of said first and second sets being aligned and spaced apart to form a cuttable web therebetween such that said base plates can be cut to length at said web and at each edge aligned with a slot from said first set and a slot from said second set.

4. A modular interior signage assembly as defined in claim 1 further characterized by:

said undercut side flanges of said sign plates having a bevel cant,

said flanges of said pair of base plates being canted outwardly from said base plate to complement a canted angle of said undercut side flanges of said elongated sign plates.

5. A modular interior signage assembly as defined in claim 1 further characterized by:

a spring clip interposed between two adjacent flanges in said first set of flanges;

said end cap having a hook that engages a protrusion interposed between said edge of said base plate and said first set of flanges with said spring clip biasing said hook section to retain engagement with said protrusion.

6. A modular interior signage assembly as defined in claim 5 further characterized by:

spring clip having a rear extending leg portion that is engageable in an aperture positioned between said two adjacent flanges in each of said base plates.

7. A base plate for an interior signage assembly, said plate comprising:

a first set of a plurality of elongated slots that extend between opposing edges of the base plate, a first set of

5

a plurality of flanges on said base plate at opposing edges of said elongated slots for engagement to undercut side flanges of a rear facing channel of an elongated sign plate to retain said elongated plates laterally on said base plate;

said base plate having a second set of slots spaced toward an inner lateral edge of said base plate, said second set of slots having a second set of a plurality of flanges on said base plate at opposing edges of said elongated slots of said second set for engagement to said undercut side flanges of the rear facing channel of said elongated sign plates to retain said plates laterally on said base plate, said second set of flanges being staggered with respect to said first set of flanges to retain said elongated sign plates at different positions than the elongated sign plates mounted on said first set of flanges. ¹⁵

8. A base plate for an interior signage assembly as defined in claim **7** further characterized by:

6

said first and second set of slots being aligned and spaced apart to form a cuttable web therebetween such that said base plate can be cut to length at said web and at each edge aligned with a slot from said first set and a slot from said second set.

9. A base plate for an interior signage assembly as defined in claim **8** further characterized by:

a protrusion interposed between said edge of said base plate and said first set of flanges that is engageable with a hook of an end cap and said channel between said flanges seatable with a spring clip that biases said hook to retain engagement of the protrusion with the hook.

10. A base plate for an interior signage assembly as defined in claim **7** further characterized by:

said flanges being canted outwardly from said base plate to complement undercut side flanges in said elongated sign plates.
